Maurice Block

UNITED STATES PATENT OFFICE.

LOUIS I. PEKOWSKY, OF NEW YORK, N. Y.

CLOTH HAT.

Application filed July 18, 1928. Serial No. 293,587.

This invention relates to improvements in cloth hats for children, and has for one of its objects the provision of a child's hat having a flexible zone or area at the juncture of 5 the crown and brim thereof, to permit the hat to be expanded within limits of several hat sizes.

Another object of the invention is to provide in a hat of this nature, an elastic band 10 having means thereon whereby the crown and brim of the hat may be suitably joined to provide a stretchable area at the portion of the hat which fits about the head of the wearer so that the hat will more readily 15 conform to the shape of the head and stretch within limits embracing several hat sizes.

A further object of the invention is to produce a hat of this nature in which the maximum simplicity of construction is secured.

20 A still further object of the invention is to provide a hat of this nature with a hat band so attached thereto as not to hinder or restrict the expansibility of the said hat.

Other objects and advantages will appear 25 as the nature of the improvements is better understood, the invention consisting substantially in the novel arrangement and co-relation of parts herein fully described, and illustrated in the accompanying drawings, where- 30 in similar reference characters are used to describe corresponding parts throughout the several views, and then finally pointed out and specifically defined and indicated in the appended claims.

35 The disclosure made the basis of exemplifying the present inventive concept suggests a practical embodiment thereof, but the invention is not to be restricted to the exact details of this disclosure, and the latter, therefore, is to be understood from an illustrative, 40 rather than a restrictive standpoint.

In the drawings forming a part of this specification:

Figure 1 is a side view in elevation of one 45 form of my improved hat with a portion of the brim broken away.

Fig. 2 is a similar view partly in section.

Fig. 3 is a fragmental sectional view showing a modified form of my invention.

Fig. 4 is a cross section of a modified form of the flexible band.

Fig. 5 is a side view in elevation of another embodiment of my invention and

Fig. 6 is a view similar to Fig. 5 partly in section.

Referring now to Figs. 1 and 2 of the drawings, 5 indicates a child's hat preferably made of cloth provided with a crown 6 and a brim 7. Intermediate the lower end 8 of the crown 6 and the lower turned over end 9 of the brim 7, I have provided a stretchable band 10 preferably made of a knitted fabric and provided with a central portion 11 terminating at the top and bottom thereof in substantially V shaped channel sections 12 and 13 respectively. The lower end 8 of the crown 6 extends into the channel 12 and is secured therein by a row of stitches 14 and the brim end 9 is similarly secured in the channel 13 by a row of stitches 15.

In Fig. 3, I have shown a modified form of my invention, in which the flexible area is provided by means of an inner knitted stretchable band 16 and an outer similar 75 band 17 between which the crown and brim is secured by rows of stitches 18 and 19 respectively.

In Fig. 4 I have shown another modified form of the flexible zone forming means 80 which consists of an inner flexible band 20, an outer flexible band 21 united near their top and bottom edges, by rows of stitches 22 and 23 or by any other suitable means, to form upper and lower channels 24 and 25, 85 in which the crown and brim of the hat is secured.

Referring now more particularly to Figs. 5 and 6 of the drawings, wherein I have shown another embodiment of my invention, 90 30 indicates an outer hat band secured by a row of stitches 31 to the inner fold of the brim 7. The hat band is secured to the said fold before it is bent over.

It will be noted by referring to Fig. 6 95 that by securing the hat band 30 to the brim 7 an annular space 32 is provided between the said band and the crown 6 and knitted band 10 so as to permit unrestricted stretchability to the hat at this area.

It will be noted that in all the forms of my invention just described there is provided a space of considerable width between the crown and brim, thus permitting full

expansion of the hat at this zone without undue restriction by either the crown or brim.

From the above it will be seen that I have provided a hat of simple and efficient construction and one that will readily stretch within limits embracing several hat sizes, and will snugly fit the head of the wearer without binding.

10 Having described my invention what I claim as new and desire to secure by Letters Patent is:

1. A hat comprising a crown and brim, an elastic area intermediate the adjacent edges of the said crown and brim, and a hat

band secured to the brim spaced from the crown, and unattached thereto to permit the hat to expand at the said area.

2. A hat comprising a crown and brim with their adjacent edges in spaced relation to each other, an elastic band intermediate the said edges, a channel on each edge of the flexible band providing means for enclosing the adjacent edges of the crown and brim within the band and an outer hat band secured to the inner side of the brim, spaced from and unattached to the crown to permit of expansion of the flexible band.

LOUIS I. PEKOWSKY.
